UNITED STATES PATENT OFFICE.

HERMAN HEYER, OF OSSINING, NEW YORK.

BURGLARPROOF WINDOW LOCK.

Application filed November 28, 1921. Serial No. 518,390.

To all whom it may concern:

Be it known that I, HERMAN HEYER, a citizen of the United States, residing at Ossining, New York, have invented certain new and useful Improvements in Burglar-proof Window Locks, of which the following is a specification.

This invention relates to locks or latches for windows and its object is to provide a lock which is burglar proof, one which will lock the window in either closed or any adjusted position, the locking or unlocking action of which may be temporarily suspended.

The invention consists essentially of a latch having a main bolt engaging a rack or series of projections on the window to be locked, with a supplemental bolt controlling the locking and unlocking of the main bolt whereby the main bolt is maintained in either withdrawn or extended position. To this may be added either or both automatic or manually operable means for operating the supplemental bolt. Finally there is provided means operable by change of direction of the window to be locked for extending the bolt into locked position.

I have herein described one form of my invention which is the best embodiment thereof of which I am at present informed, but it is to be understood that this embodiment is shown in an illustrative sense only and not a limiting one, for obviously my invention is capable of many different embodiments without departing from the spirit or scope thereof.

The embodiment chosen for illustration is shown in the accompanying drawings, in which:

Figure 1 shows a perspective view of one of my latches in use on the left hand side of a window although I ordinarily use it on the right hand side.

Figure 2 is a side elevation of my latch with a part of the trip in section.

Figure 3 is a plan view.

Figure 4 is a front end view.

Figure 5 is a perspective view of the main bolt turned over to show how the supplemental bolt is located therein.

Figure 6 is a view somewhat similar to Figure 5 for showing the supplemental bolt, its spring, its operating arm and the detent operated by the bolt.

Figure 7 is a rear end view of the latch.

Figure 8 is a perspective view of the main bolt looking down on its top.

Figure 9 is a longitudinal vertical sectional view through the latch showing the supplemental bolt and detent locking the main bolt in locked position.

Figure 10 shows a detail of the extending guard plate.

Figure 11 is a perspective view of the supplemental bolt looking from its rear end down on its top.

Figure 12 shows a perspective detail of the trip.

Figure 13 is a view similar to Figure 9 except that the rack has caused the supplemental bolt to be moved inwardly or to be retracted, whereby the detent is permitted to fall and release the main bolt from locking or extended position.

Figure 14 is a longitudinal sectional view taken along the line 14—14 in Figure 3.

Figure 15 shows a detail.

Figure 16 is a perspective view of the detent.

My latch or lock can be placed at either the right or left hand side of the window to be locked, so it is to be understood that the elements of the lock can be changed as to direction, for the principle of operation is the same. However as the lock will ordinarily be used on the right hand side, I have shown except in Figure 1, and will describe my lock as arranged for right hand use.

Referring now to these drawings I have designated a hollow casing at 1 provided with flanges 2 adapted to receive screws 3 to secure the lock to a window or the like. Slidable within the casing 1 is a bolt 4 having a sloping end and provided with a downwardly extending portion 5. Disposed within the bolt is a recess adapted to receive a detent having a shank 6, a collar portion 7 and a pointed end portion 8. Disposed between the part 7 and a shoulder in the bolt recess is a spiral spring 9 exerting pressure downwardly upon the detent.

Shank 6 of the detent extends upwardly into a recess 10 in the casing when the supplemental bolt is in its advanced position as more fully hereinafter described. Bolt 4 has a backwardly extending portion 11 enclosing a spiral spring 12 exerting pressure upon a supplemental bolt 13 positioned in a longitudinal recess in the main bolt. A recess 14 having a substan-

tially arc shaped portion forming its bottom is provided in the upper face of bolt 13 and is adapted to receive part 8 of the detent. A projecting portion 15 engaging part 5 of the main bolt limits movement of bolt 13 in one direction.

Suitably pivoted to the casing as by screw 16 is a trip member comprising a socket 17 within which arm 18 having a forked end carrying a friction roller has limited movement. A spring 20 within socket 17 exerts pressure outwardly against the end of arm 18. Socket 17 has a portion 21 paralleling the main body and having a tapered end 15 adapted to engage a lug 22 on the extension 23 of the main bolt 4. A spring 24 exerts downward pressure on the arm 18 thus tending to keep part 21 in engagement with part 22 (Fig. 15).

20 It may be found desirable to provide a hook shaped part 24^a suitably attached to the bolt 4 cooperating with a lug 25 on the manually movable head 26 riding in a slot 26^a in the casing.

25 A pull chain 27 may also be provided being pivoted to supplemental bolt 13 through toggle links 28 and 29 with suitable connections. (Figs. 6 and 14.) A slot 30 in bolt 4 allows the bolt 13 a limited movement under actuation of the pull chain 27.

30 A guard plate 31 protecting the bolt 4 may be used to prevent undesired manual retraction of this bolt when this part is in the locked position, as by burglars.

35 The operation of the device is as follows: Assume the parts as in Figure 9 with the bolt 4 advanced between projections 32 of a rack or the like upon the upper part of a window sash as in Figure 1. To lower the 40 upper window the chain 27 is pulled which through its associated mechanism causes bolt 13 to be retracted. As this action proceeds the detent under action of its spring is forced into the recess 14, the shank 6 leaving the recess 10. Farther backward movement causes positive engagement of bolt 13 with 4 (Fig. 13) and when the limit of downward movement of the chain has been reached, the head of bolt 4 has cleared the projection 32.

50 At this extreme retracted position the ear 22 has passed over the part 21, which by action of its spring has been caused to move upwardly and interfere with further forward movement of the bolts. The window may now be freely lowered.

55 When the window reaches any desired position, a slight upward movement will cause a partial rotation of the trip about

its pivot which in turn causes part 21 to become disengaged from ear 22 (Fig. 15), and under action of the spring 12, supplemental bolt 13 is moved forward followed by bolt 4, the sloping recess 14 in bolt 4 causing the detent to move upward until shank 6 is socketed in recess 10 in the casing. The window can not now be lowered without repeating this operation. The forward movement of bolt 4 causes the pull chain to resume its initial position.

70 If it is desired to retain the bolts in retracted position, the head 26 may be moved to cause lug 25 to engage the hook on part 24.

75 The sash may be raised at any time in the usual manner, each projection first moving bolt 13 which allows the detent to fall from its socket in the casing, and bolt 4 to be retracted by further movement of the projection.

80 The guard plate 31 effectively prevents undesired tampering with the bolt from outside the window as by inserting an instrument between the upper and lower windows.

85 What I claim is:

1. In combination in a lock, a main bolt automatically lockable in extended and retracted positions, and a supplemental bolt controlling the unlocking of the main bolt from both of its locked positions.

90 2. In combination with an upper and lower window sash, a lock carried by the lower sash for locking the upper sash, said lock having a casing, a main bolt for engagement with the upper sash, said bolt having an extended locked position, a supplemental bolt engaging with said upper sash, and means operated by said supplemental bolt for releasing said main bolt from said 95 locked position.

100 3. The apparatus of claim 2 with the addition of means in engagement with a window sash to release said main bolt from withdrawn locked position.

105 4. The apparatus of claim 2 with the addition of means for rendering said releasing means inoperable by said supplemental bolt.

110 5. The device of claim 1, said supplemental bolt being moved by said main bolt and independently reciprocable thereof.

115 6. The device of claim 1, said supplemental bolt being reciprocable within and moved by said main bolt.

In testimony whereof I have affixed my signature to this specification.

HERMAN HEYER.
